FRANK SANTUS, OF FLUSHING, OHIO.

PROPELLING MECHANISM FOR GRINDSTONES.

1,152,228.

Specification of Letters Patent. Patented Aug. 31, 1915.

Application filed March 12, 1915. Serial No. 13,988.

To all whom it may concern:

Be it known that I, FRANK SANTUS, a subject of the Emperor of Austria-Hungary, and resident of Flushing, county of Belmont, and State of Ohio, have invented certain new and useful Improvements in Propelling Mechanism for Grindstones, of which the following is a specification.

This invention relates broadly to grindstones, and specifically to grindstone driving mechanism.

The primary object of the invention is to provide a grindstone having associated therewith simple mechanism whereby the same may be readily and conveniently propelled by foot power.

With this and other objects in view, the invention resides in the features of construction, arrangement of parts and combinations of elements which will hereinafter be fully described, reference being had to the accompanying drawings, in which—

Figure 1 is a side elevation of the invention; Fig. 2 is a top plan view of the same; Fig. 3 is a rear end view; and Fig. 4 is a partial side elevation, illustrating, in full lines, the movable parts occupying the limit of their forward positions and, in broken lines, the limit of their rearward positions.

Referring to said drawings, in which like designating characters distinguish like parts throughout the several views—1. indicates a table or bench mounted on supporting legs 2. Mounted on said bench at a suitable point is a pair of supports 3 in or on which is journaled a shaft 4 upon which, between said supports, is mounted a grindstone 5, a slot 6 of suitable dimensions being provided in said bench through which the under portion of said stone extends.

Journaled in suitable bearings 7 mounted on the rear end of the bench is a rocker shaft 8 which has fixed thereon a pair of oppositely disposed substantially upright arms 9; and journaled in the upper ends of said arms are trunnions 10 carried by a transversely disposed rocker member 11 which carries at its opposite ends two reversely disposed crank-arms 12. Pivots connected to said crank-arms are the rear ends of two pitmen 13 whose front ends are pivoted to two reversely disposed cranks 14 fixed on the opposite ends of the shaft 4. Rigidly mounted on the front face of the rocker member 11 midway between the ends of the latter is a bracket 15 to which is pivotally connected

the upper end of a downwardly and forwardly inclined rod 16 which is directed through a suitable slot 17 in the bench and has its opposite end pivoted to the rear end of a lever or treadle 18. Said treadle is pivoted intermediate its ends on a bracket 20 located on the under side of the bench 1 and has a foot-piece 19 on its front end located within convenient reach of the operator when the latter is seated upon the seat 21 provided at the front end of the bench.

In practice, a downward and upward rocking movement of the treadle 18 communicates, through the rod or pitman 16, a rearward and forward rocking movement to the rocker member 11, which movement imparts a rotary movement to the grindstone-carrying shaft 4, through the intermediacy of the crank-arms 12, pitmen 13 and cranks 14. A parabolic curve is described by the upper end of the pitman 16 in the movement of the latter, and in order to afford such movement, the position of the bearings for the trunnions 10 must shift back and forth slightly, as indicated in dotted lines in Fig. 4. Provision for this shifting movement is made by mounting said trunnions in the arms 9 which are located on the rocker shaft 8.

While I have described the invention more or less in detail, it will be readily understood that various changes in the form and arrangement of some of the parts may be resorted to without departing from the spirit or scope of the invention as defined in the appended claims.

What is claimed is—

1. The combination with a suitable support, of a shaft for carrying a rotatable element journaled upon said support, cranks carried by the opposite ends of said shaft, a rocker shaft journaled at the rear end of said support, substantially upright arms carried by said rocker shaft, a horizontal rocker member having its ends pivoted in said arms, reversely disposed crank-arms carried by said member, pitmen interposed between said crank arms and the first-mentioned cranks, and foot-operated means for imparting a rocking movement to said rocker member.

2. The combination with a suitable support, of a shaft for carrying a rotatable element journaled upon said support, cranks carried by the opposite ends of said shaft, a rocker shaft journaled at the rear end of said support, substantially upright arms car-

ried by said rocker shaft, a horizontal rocker member having its ends pivoted in said arms, reversely disposed crank-arms carried by said member, pitmen interposed between 5 said crank arms and the first-mentioned cranks, a treadle, and a series of levers interposed between said treadle and said rocker member whereby a reciprocating movement imparted to the former communicates a rock- 10 ing movement to the latter.

3. The combination with a suitable support, of a shaft for carrying a rotatable element journaled upon said support, cranks carried by the opposite ends of said shaft, 15 a rocker shaft journaled at the rear end of

said support, substantially upright arms carried by said rocker shaft, a horizontal rocker member having its ends pivoted in said arms, reversely disposed crank-arms carried by said member, pitmen interposed between 20 said crank - arms and the first-mentioned cranks, a bracket carried by the rocker member, a treadle, and a pitman interposed between said treadle and said bracket.

In testimony whereof, I affix my signature 25
in presence of two subscribing witnesses.

FRANK SANTUS.
